UNITED STATES PATENT OFFICE.

GEORGE W. BLAIR, OF PITTSBURG, PENNSYLVANIA.

DESIGN FOR A LAMP-CHIMNEY.

SPECIFICATION forming part of Design No. 15,384, dated September 9, 1884.

Application filed April 21, 1884. Term of patent 3½ years.

To all whom it may concern:

Be it known that I, GEORGE W. BLAIR, of Pittsburgh, in the county of Allegheny and State of Pennsylvania, have invented a new and useful Design for Lamp-Chimneys; and I do hereby declare the following to be a full, clear, and exact description thereof, reference being had to the accompanying drawings, forming part of this specification, in which—

10 Figure 1 is a side elevation of my newly-designed lamp-chimney. Fig. 2 is a view of a portion of the top of the same on a larger scale, and Fig. 3 is a similar view of a modification of the same.

15 Like letters of reference indicate like parts wherever they occur.

Heretofore lamp-chimneys have been made presenting a flared and escaloped top, the outline or periphery of the same being without 20 further ornamentation.

The leading feature of my design consists

in a ridged, corrugated, or beaded surface, the outlines of which are situate on the periphery of the flaring and escaloped top.

In the drawings, *a* represents the lamp-chimney, and *b* the flaring escaloped top thereof, along the upper and outer edges of the periphery of which are the V-shaped corrugations *c*.

What I claim, and desire to secure by Letters Patent, is—

The design for a lamp-chimney, consisting of the flaring top ornamented with an escaloped periphery, each escallop being ornamented with corrugations substantially V-shaped, as shown and described.

In testimony whereof I have hereunto set my hand this 17th day of April, A. D. 1884.

GEORGE W. BLAIR.
